[57] **CLAIM**

The ornamental design for an edge finder, substantially
as shown and described.

DESCRIPTION

FIG. 1 is a top and left front perspective view of an
edge finder showing my new design;
FIG. 2 is a left side elevational view thereof, the right
side being a mirror image thereto;
FIG. 3 is a rear elevational view thereof;
FIG. 4 is a top plan view thereof;
FIG. 5 is a bottom plan view thereof; and
FIG. 6 is a front elevational view thereof.

FIG. 1

FIG. 2

FIG. 3

FIG. 4

FIG. 5

FIG. 6
